UNITED STATES PATENT OFFICE.

WILLIAM J. SHACKELTON, OF SCOTCH PLAINS, NEW JERSEY, ASSIGNOR TO WESTERN ELECTRIC COMPANY, INCORPORATED, OF NEW YORK, N. Y., A CORPORATION OF NEW YORK.

LOADING-COIL AND METHOD OF CONSTRUCTING SAME.

1,334,321.

Specification of Letters Patent. Patented Mar. 23, 1920.

Application filed August 9, 1918. Serial No. 249,068.

To all whom it may concern:

Be it known that I, WILLIAM J. SHACKELTON, a citizen of the United States, residing at Scotch Plains, in the county of Union, 5 State of New Jersey, have invented certain new and useful Improvements in Loading-Coils and Methods of Constructing Same, of which the following is a full, clear, concise, and exact description.

10 This invention relates to the loading of telephone systems, and more particularly to means for reducing or preventing inductive interference or cross-talk between the circuits of systems in which the same loading unit is used to load more than one circuit, as may be done in the case of two physical circuits and their derived phantom circuit.

In order that the cross-talk arising in such a loading unit shall be a minimum, the mutual inductances between each of the line windings in one physical circuit and those in the other physical circuit should be equal or at least very nearly so. For, if one line winding is more susceptible than the other 25 line winding of the same physical circuit to the variations of flux accompanying speech currents flowing in the windings of the other physical circuit cross-talk currents will be set up in the first circuit due to the inequality of electromotive forces induced in its two windings and their consequent failure to balance each other; in like manner inequalities of mutual inductance between the windings may cause cross-talk 30 between either of the physical circuits and the derived phantom circuit.

Inequalities of mutual inductance may arise, for instance, from lack of homogeneity as to permeability of the core of the loading unit, such as may be caused in cores made up of laminations or the like by differences in the laminations or the closeness of their contact. The effects of such inequalities, though perhaps negligible in short lines in 45 which low voltages and small currents are encountered, become accentuated to a harmful degree under the high pressures occurring in long lines, especially in systems in which amplifying repeaters are employed.

50 It is the object of this invention to provide a loading unit in which the mutual inductances between the several windings are so closely balanced as to prevent appreciable cross-talk under severe service conditions;

a further object is to afford a method for 55 producing such a condition of balance.

Further objects and advantages of this invention will be apparent from the following detailed description read in connection with the accompanying drawings, in 60 which Figure 1 represents the application of a loading unit employing this invention to the simultaneous loading of two physical circuits and their derived phantom circuit; Fig. 2 illustrates diagrammatically the windings employed; Fig. 3 illustrates more in detail the type of core used in the loading unit shown in Fig. 1; Fig. 4 shows the invention incorporated in a different form of loading unit; and Fig. 5 illustrates diagrammatically the windings employed in Fig. 4. 70

Referring to Fig. 1, I indicates one physical circuit comprising the line conductors 101 and 102, II indicates the other physical circuit comprising the line conductors 103 and 104 and III indicates a phantom circuit derived from such physical circuits in a well-known manner. The loading unit illustrated in this figure has four semi-annular core sections 1, 2, 3 and 4, joined 80 together in such manner as to form in effect two complete rings intersecting at right angles on a common diameter. The two rings may be of any suitable magnetic material but are preferably formed of finely 85 divided iron with the individual particles insulated from one another, this material being molded under high pressure into the required form. As shown in Fig. 3 the members of the core may be built up of a 90 plurality of layers or laminations 5, which may be secured together in any appropriate manner. A core of this type is described in detail in Speed Patent 1,221,238, dated April 3, 1917. 95

The core sections 1, 2, 3 and 4 are provided with the main windings 10—11, 12—13, 14—15 and 16—17, respectively. Upon each core section there is also mounted a supplementary or auxiliary winding preferably 100 surrounding a portion of the main winding. The supplementary winding on each core section is connected in series with the main winding on an adjacent core section; thus the supplementary winding 110—111 on core 105 section 2 is in series with main winding 10—11 on core section 1; similarly supplementary winding 112—113 on core section

4 is in series with main winding 12-13 on core section 3, supplementary winding 114-115 on core section 3 is in series with main winding 14-15 on core section 2, and 5 supplementary winding 116-117 on core section 1 is in series with main winding 16-17 on core section 4. In this arrangement, when the loading unit is connected to the line conductors as indicated in Fig. 1, 10 the main windings on one pair of opposite core sections, as 1 and 3, or 2 and 4, and the supplementary windings on the other pair of opposite core sections, *i. e.*, 2 and 4, or 1 and 3, are in series in one of the physical circuits, as I or II respectively; that is, 15 the core sections having main windings for either physical circuit alternate with core sections carrying the supplementary windings belonging to that physical circuit.

20 After the core sections 1, 2, 3 and 4 have been assembled, with the main windings arranged thereon so as to approach, as nearly as is practicable by means of a preliminary design, to an equality of mutual inductance 25 between the respective windings, the supplementary windings are placed on the core, their position and number of turns being determined in the following manner:

30 A closed circuit is formed which comprises a telephone receiver and the windings on two opposite core sections, for instance windings 14-15 on core section 2 and windings 16-17 on core section 4, the core windings being connected in this circuit in the 35 same relation as would be the case in physical circuit II as shown in Fig. 1 of the drawings. A current of telephonic frequency is applied to one of the other main windings, as winding 10-11 on core section 40 1; this current produces a varying magnetic flux in core section 1, which flux divides at the junction points of the core sections and passes through the core sections 2, 3 and 4.

45 Since the two portions of the flux in sections 2 and 4 pass in opposite directions through the material of the ring formed by these sections while the turns of windings 14-15 and 16-17 follow the same direction around the ring, it is apparent that the 50 electromotive force induced in winding 14-15 will be opposed to that of winding 16-17, as regards the effect of these forces in producing a current in the test circuit. Consequently if the two electromotive forces are 55 equal in magnitude, as will be the case if the mutual inductance between the windings 10-11 and 14-15 is equal to the mutual inductance between the windings 10-11 and 16-17, no current will flow in the test 60 circuit including the windings 14-15 and 16-17 and the telephone receiver. But, if, because of differences in permeability between the core sections 2 and 4 or of the 65 lack of symmetry of the two core sections and the windings 14-15 and 16-17 with respect

to the core section 1 and its winding 10-11 or from other causes, the mutual inductance between the winding 10-11 and the winding 14-15 is not the same as the mutual inductance between the winding 10-11 and the winding 16-17, the electromotive forces in the windings 14-15 and 16-17 will not balance and vibratory current will be set up in the circuit including the windings 14-15 and 16-17, and consequently the telephone receiver will be energized.

70 The wire forming the continuation of one of the terminals as 11 of the main winding 10-11 is thereupon wrapped a number of times around one of the adjacent core sections, for instance 2, to form the supplementary winding 110-111, the number and direction of its turns and their position on the core section being adjusted by trial to 75 reduce the tone in the telephone receiver to a minimum, that is, to introduce into the core section 2 additional flux of such strength and direction as to counterbalance, as nearly as possible, the difference between the inductance from winding 10-11 to winding 14-15 and that from winding 10-11 to winding 16-17. Current of telephonic frequency is next applied to winding 12-13 in 80 core section 3, the windings 10-11 and 16-17 being connected in the test circuit 85 as before. The wire forming the terminal 13, for instance, of the main winding 12-13, is formed into a supplementary winding 112-113 on the core section 4, this winding being adjusted, in the same manner as 90 was supplementary winding 110-111, until the tone in the telephone receiver is again 95 reduced to a minimum.

100 The above procedure establishes in the loading unit substantial balance of the inductive effects of line conductor 101, represented by windings 10-11 and 110-111, upon windings 14-15 and 16-17 respectively, and independently establishes a like 105 condition with respect to the inductive effects of line conductor 102, represented by windings 12-13 and 112-113, upon windings 14-15 and 16-17 respectively. This 110 results in reducing the inductive interference or cross-talk arising in the coil between the physical or side circuit I, and physical or side circuit II, and also between the derived phantom circuit III and the physical circuit II.

115 In the same way currents of telephonic frequency are applied to the windings 14-15 and 16-17 respectively, and supplementary windings 114-115 and 116-117 respectively are placed in series with these main windings and adjusted upon the core sections 3 and 1. This further reduces the cross-talk between the side circuits I and II and also reduces the cross-talk between the phantom circuit III and the side circuit I.

120 This method when applied to a loading 130

unit of the type above described, has reduced the cross-talk between the physical circuits to about one-twelfth of its former magnitude and the cross-talk between the 5 phantom circuit and the physical circuits to about one-sixth of its former magnitude.

The modification shown in Figs. 4 and 5 involves the application of this invention to a simple toroidal coil comprising a plurality 10 of core sections 6, 7, 8 and 9. On each of the four core sections are placed an inner and an outer main winding section, the outer winding section on one core section and the inner winding section on the opposite core 15 section forming a main winding for one of the line conductors, the sections of the main winding for the other line conductor of the same physical circuit being arranged in the reverse order on this same pair of opposite 20 core sections, as described in Campbell-Shaw Patent 980,921, issued January 10, 1911, and Fondiller Patent 1,210,628 issued January 2, 1917.

In series with each of the four two-section 25 main windings is a supplementary winding, which is placed upon one of the core sections between the core sections which carry the main winding sections. Thus the physical circuit I includes as part of one line conductor 30 for the main winding section 20-21 on core section 6, main winding section 22-23 on core section 8 and supplementary winding 120-123 on core section 7, and also includes in series therewith as part of the other line 35 conductor, main winding section 28-29 on core section 6, main winding section 30-31 on core section 8 and supplementary winding 128-131 on core section 9, the main winding sections 24-25 and 26-27, supplementary 40 winding 124-127, main winding sections 32-33 and 34-35, and supplementary winding 132-135 being similarly arranged in physical circuit II. The supplementary windings 120-123, 124-127, 128-131 and 45 132-135 are adjusted in the same way as described in connection with the supplementary windings shown in Fig. 1.

It is to be understood, of course, that it is not essential in all cases that there be a 50 supplementary winding on each core section, since cases may occur where one or more of the supplementary windings may be omitted. It is also within the scope of this invention to place both the supplementary 55 windings that are included in one physical circuit upon either one of the core sections whose main windings are in the other physical circuit, provided that the number and direction of turns are properly 60 adjusted. Other modifications may also be made, as required by the circumstances under which the invention defined in the subjoined claims are to be used.

What is claimed is:

65 1. The method of compensating for dif-

ferences in permeability between sections of the core of an inductance coil which carry the different main windings for the physical circuits in which the coil is to be connected, which consists in connecting to each main 70 winding a supplementary winding and adjusting by trial said supplementary windings on sections of the core adjacent to the sections carrying the windings with which said supplementary windings are connected. 75

2. The method of compensating for differences of mutual inductance between the windings of a loading coil adapted for use with two physical circuits and a derived phantom circuit and which comprises a core 80 on which the windings of one physical circuit are arranged alternately with the windings of the other physical circuit, which consists in including in series with each physical circuit winding a supplementary 85 winding mounted on an adjacent section of the core and adjusting by trial the number and direction of turns of said auxiliary windings to balance inductively the windings of each physical circuit with respect 90 to the windings of the other physical circuit both for side working and for phantom working.

3. The method of compensating for differences of mutual inductance between the 95 windings of a loading coil adapted for use with two physical circuits and a derived phantom circuit and which comprises a core on which the windings for one physical circuit are arranged alternately with the windings for the other physical circuit, which 100 consists in including in series with one winding of one physical circuit a supplementary winding mounted on the same section of the core as one winding of the other physical circuit and adjusting by trial said supplementary winding so as to produce equal mutual inductances between said first named winding and each of the two windings of the second physical circuit, repeating said 105 operation with the other winding of first physical circuit and the windings of the second physical circuit, and repeating both of said operations in turn with each winding of the second physical circuit and the 110 main windings and supplementary windings of the first named physical circuit.

4. The method of reducing the inductive interference between the windings of the respective circuits in an inductance coil 120 adapted for simultaneously loading two physical circuits and a derived phantom circuit, which consists in connecting the windings for one physical circuit in series with a telephone receiver or the like in the 125 same relation that said windings are to be connected in said physical circuit, placing on the section of the coil including one of said windings a supplementary winding connected to one of the windings for the 130

other physical circuit, passing a current of telephonic frequency through said last named winding and the supplementary winding, and adjusting the supplementary winding until the tone produced in the telephone receiver is a minimum, and repeating said procedure with each of the remaining windings and the two windings for the physical circuit in which said winding is not to be connected. In witness whereof, I hereunto subscribe my name this 5th day of August A. D., 1918.

10
